United States Patent Office.

WILLIAM S. ROCKWELL, OF SAVANNAH, GEORGIA.

Design No. 2,733, dated August 6, 1867.

DESIGN FOR A PILLAR.

The Schedule referred to in these Letters Patent and making part of the same.

TO ALL WHOM IT MAY CONCERN:

Be it known that I, WILLIAM S. ROCKWELL, of Savannah, and in the State of Georgia, have invented certain new and useful Improvement in Design for the Pillar of the Porch; and do hereby declare that the following is a full, clear, and exact description thereof, reference being had to the annexed drawings, and to the letters of reference marked thereon, making a part of this specification.

My invention consists in the design of a pillar of the porch which ornamented the Temple of King Solomon, and is intended for use in masonic assemblies.

In the annexed drawings, A represents the solid column, which is fluted, as shown, and can be made of brass or other suitable material. This column is surmounted by chapters, the chapters being composed of seven (7) wreaths of twisted brass a set perpendicularly on an abacus of seven (7) sides crowning the shaft of the pillar. Upon four of these wreaths, in a trapezoidal form, is suspended a latticed net-work of brass and copper, (see B, figs. 1 and 3,) colored yellow and red, around the curved bottom of which is a brazen fringe ornamented with two rows of brazen pomegranates, fifty in a row. Within the net-work B is set a hollow silver lily with six (6) pointed leaves. This lily circumscribes a sphere of brass, D, whose diameter is exactly equal to the diameter of the top of the column, and whose superior convex surface reaches an elevation above the abacus.

Having thus fully described my invention, what I claim, and desire to secure by Letters Patent, is—
The within-described design for "pillar of the porch," as set forth.

In testimony that I claim the foregoing, I have hereunto set my hand this 9th day of July, 1867.

WM. S. ROCKWELL.
